BUFFER

Filed Oct. 5, 1931

UNITED STATES PATENT OFFICE

SVEN BÄCKSTRÖM, OF HELSINGFORS, FINLAND

BUFFER

Application filed October 5, 1931. Serial No. 567,034.

This invention appertains to new and useful improvements in cleaning implements and more particularly to a novel polishing device, particularly adapted for polishing automobile bodies and particularly painted surfaces.

The principal object of this invention is to provide a buffer or polisher which because of its shape, is capable of reaching remote points and crevices.

Other important objects and advantages of the invention will become apparent to the reader of the following specification.

In the drawing:—

15 The figure represents a longitudinal sectional view through the implement.

Referring to the drawing it can be seen that numeral 5 represents a frusto-conical-shaped casing, open at one end, and at this 20 end provided with a removable header 6 of cup-shape and having projecting outwardly from the central portion thereof, a hollow shank 7, within which a switch 8 can be located, with a lever 9 for operating the same 25 projecting therefrom, through an opening 10 in the shank, and through an opening 11 in the tubular covering 12 for the shank. A cover 13 of suitable insulating material is secured to the outer end of the shank, and 30 has an opening therethrough through which the conductive wire 14 to the switch 8 can be trained.

Within the shell 5 is a motor including the 35 field coil or coils 15 and the armature 16 operating therein and driving the armature shaft 17, which at one end is journaled into the header 6 as at 18 and at its opposite end, as at 19, in the thickened portion 20 of the 40 conical-shaped casing 21.

At the reduced end of the shell 5 and exteriorly thereof, is the gear 22 suitably secured to the armature shaft 17 and meshing with the intermediate gears 23 on the counter 45 shafts 24. Smaller gears 25 are also keyed to

the counter-shafts 24 and mesh with the ring gear 26 on the inside of the casing 21.

Numeral 27 represents the usual commutator, and numeral 28 represents the usual brushes engaging the commutator, while numeral 29 represents the conductor wires extending from the switch 8 to the field of the motor, with the wires 30 indicating the connections between the field and the brushes 28.

A cup-shaped shell 31 is externally threaded at its enlarged end for engagement into the enlarged end of the casing 21, whereby the casing and shell 31 are fixed together. Interposed between the reduced end of the shell 31 and the shank 7, is a ball bearing 50 anti-frictional mount 32, so that the shell 31 rotates around the shank 7.

A resilient pad of rubber or the like is denoted by numeral 33 and is suitably secured over the entire outer surface of the casing 55 21 including the thickened end portion 20. A jacket of cloth or other suitable material 34 can be arranged over this pad 33 in a removable manner, so that when the same becomes soiled, the same can be removed and 60 replaced by another cloth.

It can now be seen, that by operating the switch 8 to close the motor circuit, the motor can operate to drive the armature shaft 17 and through the gears 22, 23 and 25, operate the shell 21 which carries a pad 65 33 and covering 34.

While the foregoing specification sets forth the invention in specific terms, it is to be understood that numerous changes in 70 the shape, size and materials may be resorted to without departing from the spirit and scope of the invention as claimed herein-after.

Having thus described my invention, what 75 I claim as new is:

1. A buffer of the character described comprising a hollow conical-shaped casing, a covering for the casing, a shell projecting inwardly of the large end of the casing, a mo- 80 90

tor in and concentric with the shell, said shell being provided with a handle journaled through the large end of the casing, drive means between the motor and the casing,
5 said drive means comprising a shaft driven by the motor, a ring gear on the inner side of the casing, and gears between the shaft and the ring gear.

10 2. A buffer as described in claim 1 and having the apex portion of the case thickened and recessed to provide a socket, and a bearing mounted within the socket for journally receiving the shaft.

In testimony whereof I affix my signature.
15
